(57) **CLAIM**

Applicants claim the ornamental design for a power coil universal plug, as shown and described.

DESCRIPTION

FIG. 1 is a top perspective view of a power coil universal plug showing our new design.

FIG. 2 is a left side elevation thereof.

FIG. 3 is a right side elevation thereof.

FIG. 4 is a top plan view thereof.

FIG. 5 is a bottom plan view thereof.

FIG. 6 is a front elevation view thereof; and,

FIG. 7 is a rear elevation view thereof.

The broken line in FIG. 7 is included for the purpose of illustrating unclaimed environment only and forms no part of the claimed design.
